UNITED STATES PATENT OFFICE

100,788

DESIGN FOR A FLOOR CONDITIONING MACHINE

Harry L. Myers, Toledo, Ohio, assignor to The
American Floor Surfacing Machine Company,
Toledo, Ohio, a corporation of Ohio

Application June 24, 1936, Serial No. 63,462

Term of patent 14 years

To all whom it may concern:

Be it known that I, Harry L. Myers, a citizen of the United States and resident of Toledo, in the county of Lucas, and State of Ohio, have invented a new, original, and ornamental Design for a Floor Conditioning Machine, of which the following is a specification, reference being had to the accompanying drawing forming a part thereof.

Figs. 1 and 2 are perspective views, taken from different sides, of a floor conditioning machine, showing my new design, and Fig. 3 is a rear per-

spective view thereof with the dotted parts partly broken away.

The dominant feature of my new design resides in the stepped configuration of the top portion of the machine, substantially as shown.

I claim:

The ornamental design for a floor conditioning machine, substantially as shown and described.

In testimony whereof I have hereunto signed my name to this specification.

HARRY L. MYERS.
